219,559

ELECTRIC FISHING MOTOR CONTROL HEAD

Harold D. Fetty, Detroit, Mich., assignor to Osborn
Engineering Corporation, a corporation of Delaware

Filed Oct. 23, 1969, Ser. No. 19,689

Term of patent 14 years

Int. Cl. D12—99

U.S. Cl. D71—1

FIG.1

FIG.2

FIG.3

FIG.4

FIG.5

FIG. 1 is a perspective view of the fishing motor control head;

FIG. 2 is a top view of the control head illustrated in FIG. 1;

FIG. 3 is a side view of the control head illustrated in FIGS. 1 and 2;

FIG. 4 is a front view of the control head illustrated in FIGS. 1-3; and

FIG. 5 is a rear view of the control head illustrated in FIGS. 1-4.

The broken lines are for illustrative purposes only.

I claim:

The ornamental design for an electric fishing motor control head, substantially as shown and described.
